DESIGN FOR AN ORTHOPEDIC CARRIAGE

Amy J. Daniels, Palmer, Mass.

Application October 19, 1936, Serial No. 65,346

Term of patent 14 years

To all whom it may concern:

Be it known that I, Amy J. Daniels, a citizen of the United States of America, residing at Palmer, in the county of Hampden and State of Massachusetts, have invented a new, original, and ornamental Design for an Orthopedic Carriage, of which the following is a specification, reference being made to the accompanying drawings forming a part thereof.

Fig. I is a perspective view of an orthopedic carriage showing my new design;

Fig. II is an elevational view showing the other end of the carriage shown in Fig. I; and

Fig. III is an elevational view showing the other side of the carriage shown in Fig. I.

I claim:

The ornamental design for an orthopedic carriage substantially as shown.

AMY J. DANIELS.
